WHEEL MAKING MACHINE

Alexander D. Matheson, Davenport, Iowa, assignor to French & Hecht, Incorporated, a corporation of Iowa

Application March 31, 1939, Serial No. 265,175

1 Claim. (Cl. 78—16)

This invention relates to wheel making machines of the general organization represented in U. S. Letters Patent No. 640,548, wherein a wheel hub and rim to be connected by spokes are supported in the machine in concentric relation to one another and heated spokes inserted through aligned openings in the rim and hub and upset endwise simultaneously to head over the end of the spoke inside the hub and form a shoulder on the spoke to bear against the outer surface of the hub. While the present invention is adapted generally to the form of machine shown in the patent referred to, it finds its particular application in the machine as shown and described in a copending U. S. application Ser. No. 265,204, filed by John H. Ploehn, to which reference may be had for a detailed understanding of the entire machine.

In these machines, the hub and rim are supported on a pivotally mounted gooseneck table, the lower arm of which is adapted to support the hub and rim and the upper arm to carry a clamp for securing the hub in position on the table. The machine is operated pneumatically, its successive operations during each cycle being controlled by valves actuatable by a foot treadle. Initially, the table occupies a position with its front end tilted upward for the insertion of a spoke through the openings in the rim and hub, and when the cycle of operation of the machine is inaugurated by a partial depression of the foot treadle, air is exhausted from a table-lifting cylinder, allowing a piston therein to descend and permitting the front end of the table to drop into operative position to lower the hub over a spoke heading tool or header and locate the portion of the spoke outside the hub between a pair of vise jaws. Further depression of the foot treadle effects the admission of air into a cylinder to raise a piston therein for actuating the vise jaws to clamp and hold the spoke against movement during the upsetting operation. After the spoke is clamped between the vise jaws, depression of the foot treadle through the remainder of its downward stroke causes the header inside the hub to move forwardly toward the vise jaws to upset and head over the heated end of the spoke against the inner surface of the hub. At the same time, the table supporting the hub moves in the same direction as the header, but only half as far, causing the portion of the spoke between the outside of the hub and the vise jaws to be upset to form the shoulder, the vise jaws being equipped with dies into which the displaced metal flows and by which it is confined to force it against

the outer surface of the hub and mold it to the desired shape. When the upsetting operation is completed, relief of the pressure on the foot treadle permits its return stroke and the machine operates by the exhaust of air from the header and vise jaw actuating cylinders to effect the retraction of the table and header and the opening of the vise jaws to release the spoke, and by the admission of air to the table-lifting cylinder to tilt the front end of the table to its original upper position so that the spoke clears the top edges of the vise jaws. The hub clamp is then released to permit the turning of the hub and rim to the proper position for operation on another spoke. The operation of the machine as just set forth is repeated for each successive spoke.

In the operation of the machine, it is necessary to adjust the front end of the table vertically to different set positions according to the length of the hub to be operated upon or because of various angularities of the hub walls, which frequently are not parallel with the axis of the hub. When, as is sometimes the case, the spoke holes in the hub walls are not uniformly located lengthwise of the hub (vertically when the hub is positioned on the table), it is necessary to vary the vertical position of the front end of the table for each individual spoke. Heretofore, the table-lifting cylinder has been stationarily mounted on the base of the machine and the only means of adjusting the vertical position of the front end of the table comprised a screw connected to the table and to the piston in the stationary cylinder. With this arrangement, each time the table had to be adjusted to a different position it was necessary to reach down underneath the table with a hand wrench and adjust the screw connecting the table and table lifting piston, a method which was laborious, crude and slow.

It is the object of the present invention to obviate these and other objectionable features of the prior art and to provide means for rapidly, accurately and conveniently adjusting the front end of the table to a given set position.

To this end, and in its broader aspects, the present invention contemplates the provision of means for vertically adjusting the front end of the table and means operable to control the operation of the adjusting means and located remote therefrom. More specifically, the invention provides an arrangement wherein the table and its lifting mechanism are adapted to be raised and lowered as a whole by a screw jack on which the lifting mechanism is mounted and which is operated by a hand wheel located near the front of

the machine. In carrying out the invention, the table is connected to the rod of the table lifting piston which, in its lower position, rests on the head of the table-lifting cylinder, the cylinder, in turn, being mounted for vertical movement and supported on a low pitch screw jack adapted to be operated through a series of gears and gear shafts by a hand wheel conveniently located at one side of the machine near the front end thereof, whereby rotation of the hand wheel in one direction or the other raises or lowers the table and table lifting mechanism as a whole; and the low pitch of the threads of the screw jack enables such adjustment to be made easily and accurately and also serves as a positive lock to maintain the table in the exact position to which it is adjusted.

Referring to the drawings:

Fig. 1 is a side elevation of the machine, showing by the dot and dash lines the tilted position of the wheel supporting table;

Fig. 2 is a cross-section taken approximately on the line 2—2 of Fig. 4, looking in the direction of the arrows, some of the parts being broken away to show the construction;

Fig. 3 is a fragmentary sectional elevation taken approximately on the line 3—3 of Fig. 4, looking in the direction of the arrows;

Fig. 4 is a side elevation of the table lifting and adjusting mechanisms, partly in section and partly broken away, to show the structure;

Fig. 5 is a sectional plan view taken on the line 5—5 of Fig. 2, looking in the direction of the arrows; and

Fig. 6 is a sectional plan view taken approximately on the line 6—6 of Fig. 2, looking in the direction of the arrows.

Referring particularly to Figs. 1 and 2, the machine comprises a base 1 on which front, rear and intermediate pedestals 2, 3 and 4, respectively, are mounted and which support two horizontal parallel guide bars 5 and 6, which are circular in cross-section, these parts constituting the main frame of the machine. Mounted in the frame are the three fundamental units of the machine, namely, the work supporting table 7 with its associated hub-clamping ram 8 and lifting cylinder 9, the spoke-clamping vise jaws 10 and their actuating cylinder 11, and the header 12 and its actuating cylinder 13.

The work supporting table 7 comprises upper and lower arms 14 and 15 spaced apart vertically at the front and joined together at the rear by bolts 16 passing through flanges 17 and 18 on the upper and lower arms, respectively, and through spacing members 19 and 20 between the rear ends of the table arms 14 and 15, the member 20 being adapted to be replaceable by one of different thickness to vary the vertical distance between the upper and lower arms when desired. The front end of the lower arm 15 of the table 7 is pivotally mounted on studs 21 (one only being shown) at opposite sides of the front end of a slide 22 which is arranged for reciprocation on a plate 23 by which the table unit is pivoted as at 24 to a collar 25 on the rear pedestal 3, the slide 22 having a dovetail connection 26 with the plate 23, as best seen in Fig. 2. A threaded stud 27 is pivotally connected to the rear end of the slide 22 and adapted to extend upwardly through an extension 29 of the spacing member 19, adjusting and lock-nuts 30 being provided on the stud on opposite sides of the extension 29 for raising and lowering the rear end of the table 7 relatively to the slide 22 to locate the

table according to the angle of the spoke openings 31 in the hub, the front end of the table rocking about the studs 21 by which it is connected to the slide. The weight of the table 7 is counterbalanced by a weight 76 supported at 5 the rear of the machine on a rod 77 pivoted to the end of an arm 78 whose opposite end is secured to the side of the spacing member 19 between the arms 14 and 15 of the table, so that in operation the table lifting and adjusting means 10 are relieved of the burden of overcoming the full weight of the table.

The upper arm 14 of the table 7 carries the ram 8, for clamping a hub 28 (as shown diagrammatically by the broken lines in Fig. 1) on the 15 table, which is mounted for reciprocation in a fixed supporting bracket 32 secured to the forward end of the arm, and an air cylinder 33 mounted on the top edge of the arm. The clamping ram 8 is connected to the air cylinder 33 by 20 a double arm lever 34 (one arm only being shown) pivoted to the upper table arm 14 on a pin 35 intermediate the ram and the air cylinder and extending rearwardly beyond its connection 36 with the air cylinder, the free ends of the 25 lever 34 being adapted to support weights 37 to counterbalance the weight of the ram. The ram 8 is actuated by a piston 38 in the cylinder 33 and is under the control of a simple two-way valve 39 operable by the movement of a pull 30 rod 40 extending toward the front of the machine.

Toward the front end of the machine, the air cylinder 11 is mounted on the base 1 between depending arms 41 of the vise jaws 10 (one arm and one jaw only being shown) which arms are 35 rockably mounted each on one of the parallel horizontal guide bars 5 and 6. The lower end of each of the arms 41 is adjustably connected to a rod 42 of a piston within the cylinder 11, the arrangement being such that when the piston 40 rises in the cylinder, the lower ends of the arms 41 are forced outwardly in opposite directions to close the vise jaws 10 on a spoke 43 and, upon descent of the piston, the arms 41 are pulled toward one another to open the vise jaws and 45 release the spoke.

The header mechanism comprises a centrally located shaft or header bar 44 (Fig. 2) arranged between the guide bars 5 and 6 of the frame and having its front end mounted for reciprocation in a bearing in the front pedestal 2 and its opposite end mounted in a slide-block 45 supported on the guide bars 5 and 6. Intermediate its ends, the header bar 44 is slidably supported in a bearing 46 in a split cross-head 47 of the 55 intermediate pedestal 4, being held against rotation about its own axis by keys 48 arranged in keyways 49 and 50 formed therein and in the bearing 46, respectively. The air cylinder 13, located immediately in front of the rear pedestal 60 3, is equipped with a piston (not shown) having its piston rod 51 connected to a slide-block 52 mounted for vertical reciprocation in a guideway 53 formed in the front face of the rear pedestal 3, and a connecting link 54 is pivotally secured 65 at one end to the slide-block 52 and at its opposite end to the slide-block 45 which supports the rear end of the header bar 44. When the piston rises in the cylinder 13, forcing the slide-block 52 upwardly, the link 54 is moved toward a horizontal position, thus forcing the slide-block 45 forwardly on the parallel guides 5 and 6 and moving the header bar 44 and header 42 with it.

As already stated, during the spoke-upsetting operation, the table 7 is moved forwardly half 75

as far as the header bar 44. This is accomplished by pivotally securing the ends of a pair of pendant lever arms 55 (one only being shown) to opposite sides of the adjustable collar 25 on the rear pedestal 3 and connecting the opposite or lower end of each by a link 56 to one side of the slide-block 45 which supports the rear end of the header bar 44, and also pivotally securing one end of each of a pair of adjustable links 57 substantially midway between the ends of the pendant lever arms 55 and connecting the opposite end of the link 57 to the side of the table slide 22. Thus, when the slide-block 45 supporting the rear end of the header bar 44 moves forwardly, it pulls the lever arms 55 through the connecting links 56 attached thereto, and this movement of the lever arms acts through the links 57 connecting them with the table slide 22 to move the table 7 in the same direction as the header bar. However, since the links 57 are connected midway between the ends of the lever arms 55, the movement imparted to the table is only half that of the header bar. When air is exhausted from the cylinder 13 and the piston therein descends, the header bar 44 and table 7 are returned to their normal positions by springs 58 and 59 secured at one end to the slide-block 45 and having their opposite ends anchored to a fixed part of the machine.

The table lifting mechanism comprises the air cylinder 9 with the piston 60 therein having its rod 61 connected to the table by vertical side links 62. The piston 60 rests on the cylinder head 63 when in its lower position and the piston rod 61 is screw threaded into a cross-head 64 extending toward opposite sides of the machine and arranged to slide vertically on a pair of guide rods 65 secured at their lower ends in bosses 66 on opposite sides of the cylinder 9 and at their upper ends in a cross-head 67 which carries a stop 69 adapted to be engaged by the end of the piston rod 61 for limiting the upward stroke of the piston 60. The lower ends of the links 62 are secured as at 70 to the opposite ends of the cross-head 64 and extend upwardly through bearings 71 formed in the ends of the pedestal 4 and in which they are adapted to slide vertically but are restrained against movement in any other direction. The upper ends of the links 62 are in the form of T-shaped heads 72, formed each with an elongated slot 73 adapted to accommodate a roller 74 mounted on a stud 75 secured to the table slide 22. With this arrangement, when air is admitted into the cylinder 9, the piston 60 rises therein, carrying with it the cross-head 64 threaded on the piston rod 61 and through the connecting links 62 raises the front end of the table 7, which rocks about the pivot 24 by which the slide 22 is connected to the collar 25 on the rear pedestal 3. When the table 7 is in its lower operative position and the slide 22 is reciprocated to move the table during and after the spoke upsetting operation, the side links are held in their vertical positions in the bearings 71 and the rollers 74 move back and forth in the slots 73 in the heads of the links 62, thus permitting freedom of movement of the table slide 22 in a truly horizontal path and minimizing wear of the relatively moving parts.

According to the present invention, the table 7 and its tilting mechanism as a whole are adapted for adjustment vertically by means of a hand wheel 80 conveniently located near the front end of the machine. To this end, instead of be-

ing mounted directly on the base 1, the head 63 of the cylinder 9 is mounted on a screw jack 81, comprising a square-threaded screw sleeve 82 secured to the cylinder head 63 by a stud 84 screwed into a threaded opening 85 in the cylinder head and secured by a pin 86, the stud 84 being formed with a bearing surface 87 for the sleeve 82 and held thereon by a nut 88 threaded on the lower end of the stud. A bevel ring gear 89, having an internally square-threaded hub 90 10 is threaded onto the sleeve 82 and rests on a bearing 91 between it and a support 92 mounted on the base 1 of the machine, being held against vertical movement relatively to the support 92 by a cover plate 93 screwed on the lower end of 15 the ring gear hub 90 and engaging a shoulder 94 on the support 92. Thus, the ring gear 89 acts as a nut on the threaded sleeve 82 and, being capable of rotary movement only, its rotation in one direction or the other will effect a relative 20 vertical movement of the sleeve 82 and cause the cylinder 9 and associated parts to be raised or lowered as the case may be.

The ring gear 89 is adapted to be rotated by the hand wheel 80 through a series of bevel gears 25 and the shafts on which they are mounted. Thus, a bevel gear 95 adapted to mesh with the ring gear 89 is mounted on one end of a shaft 96 journaled in a bearing 97 on the base 1 and having fixed to its opposite end a bevel gear 98 30 meshing with another bevel gear 99 fixed to the lower end of a shaft 100 extending upwardly at an angle along the side of the machine, the shaft 100 being removably secured near its opposite ends by straps 101. The upper end of the 35 shaft 100 has a bevel gear 102 fixed to it and arranged to mesh with a bevel gear 103 fixed to one end of a shaft 104 journaled in a bracket 105 secured to the main frame and on the opposite end of which shaft the hand wheel 80 is 40 mounted.

In order to support and guide it in its vertical movement, the cylinder 9 has fastened to its top edge, as by bolts 106 (Fig. 5), a bracket 68 whose base 107, extending beyond the peripheral 45 surface of the cylinder 9, is formed with lateral recesses 108 adapted to receive tongues 109 formed on a guide bracket 110 secured rigidly by bolts 111 to the rear face of the intermediate pedestal 4. The cross-head 64 is formed near its opposite ends with lugs 112 having open ended slots 113 adapted to receive tongues 114 formed on the guide bracket 110 and adapted by their sliding engagement in the slots 113 to prevent twisting of the cross-head 64. Hence, although free 50 to move vertically, the cylinder 9 and cross-head 64 are restrained rigidly against movement in any other direction.

With the foregoing arrangement, when the hub 28 is placed on the table 7 and it is required that the front end of the table be adjusted vertically properly to locate the hub and the spoke 43 relatively to the vise jaws 10 and the header 12, the hand wheel 80 is rotated in one direction or the other to raise or lower the table as required. The rotation of the hand wheel 80, through the intermediate series of bevel gears and shafts on which they are mounted, effects the rotation of the ring gear 89 relatively to the threaded sleeve 82 secured to the cylinder head 70 63. Since the sleeve 82 is held against rotation and the ring gear 89 is held against vertical movement, the rotation of the latter effects a relative vertical movement of the sleeve. If the hand wheel 80 is being rotated in a direction to raise the 75

table 7, the sleeve 82 will move upwardly relatively to the ring gear 89, causing the cylinder 9, piston 60 and the cross-head 64 threaded on the piston rod 61 to move upwardly and, through the arms 62, raise the table. If, on the other hand, the hand wheel 80 is rotated in a direction to lower the table, the sleeve 82 will be caused to move downwardly relatively to the ring gear 89 and carry with it the cylinder 9 and associated parts and the table 7. The movement of the cylinder 9 up and down is always effected positively by the screw jack and enables its location and, hence, the location of the table accurately in any desired position, and the low pitch 15 of the threads on the sleeve 82 and the hub 90 of the ring gear 89, causes them to serve as a positive stop to maintain the table in any adjusted position. Because the links 62 which connect the cross-head 64 and the table are arranged 20 to slide in the bearings 71 and are thus held in a truly vertical position at all times, the vertical position of the table 7 remains unchanged during the forward movement thereof to form a shoulder on the spoke during the upsetting operation.

In the accompanying drawings, the invention has been shown merely by way of example and in preferred form and obviously many modifications and variations may be made therein and in its mode of application which will still be comprised within its spirit. For example, the invention is

applicable equally as well to machines for making wheel spiders, that is, wheel hubs with spokes fastened therein and to which the rim is secured subsequently. It is to be understood, therefore, that the invention is not limited to any specific 5 form or embodiment except insofar as such limitations are specified in the appended claim.

Having thus described my invention, what I claim is:

In a pneumatically operated wheel spoke securing machine, the combination of a hub support 10 the front end of which occupies an upper inoperative position and a lower operative position, an air cylinder having a piston therein connected to the support and operable to effect the raising and lowering of the support, a fixed guiding support to which the air cylinder is connected for relative movement vertically, a gear-operated low-pitch screw-jack on which the air cylinder 15 is mounted, a hand wheel for actuating the screw-jack located remote therefrom at the front of the machine for convenient operation, and a series of gear and shaft connections between the screw-jack and the hand wheel, whereby the air cylinder and support are adapted for 20 vertical adjustment as a unit to locate the support accurately in different set operative positions and the screw-jack is adapted to be self-operative to lock the support in any adjusted position thereof.

ALEXANDER D. MATHESON.
